The ornamental design for a lumbar support, as shown and described.

DESCRIPTION

FIG. 1 is a front perspective view of a lumbar support shown in an exemplary environment according to a first embodiment;

FIG. 2 is a front view of the lumbar support;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a front perspective view thereof;

FIG. 9 is a rear perspective view thereof;

FIG. 10 is a front perspective view of a lumbar support shown in an exemplary environment according to a second embodiment;

FIG. 11 is a front view of the lumbar support;

FIG. 12 is a rear view thereof;

FIG. 13 is a side view thereof;

FIG. 14 is an opposite side view thereof;

FIG. 15 is a top view thereof;

FIG. 16 is a bottom view thereof;

FIG. 17 is a front perspective view thereof; and,

FIG. 18 is a rear perspective view thereof.

In certain embodiments, a rear portion of the lumbar support includes an electronic assembly that includes one or more massage components, one or more heating components, and/or one or more cooling components (e.g., fans).

The broken lines in the drawings illustrate portions of the lumbar support that form no part of the claimed design. The additional broken lines in FIGS. 1 and 10 illustrate an exemplary environment in which the lumbar support may be used and form no part of the claimed design.
